UNITED STATES PATENT OFFICE

146,837

DESIGN FOR A MULTITONE WHISTLE

Josephus Thompson, Covington, Ohio, assignor of one-third to Grossman Music Company, Cleveland, Ohio, a partnership composed of Julius I. Grossman and Henry S. Grossman

Application April 3, 1946, Serial No. 128,234

Term of patent 14 years

(Cl. D34—15)

To all whom it may concern:

Be it known that I, Josephus Thompson, a citizen of the United States, residing in the city of Covington, county of Miami, and State of Ohio, have invented a new, original, and ornamental Design for a Multi-tone Whistle, of which the following is a specification, reference being had to the accompanying drawing, forming a part thereof.

Figure 1 is a side view of the multi-tone whistle, embodying my new design;

Figure 2 is a top view;

Figure 3 is a front end view;

Figure 4 is a rear end view; and

Figure 5 is a bottom view thereof.

I claim:

The ornamental design for a multi-tone whistle, substantially as shown.

JOSEPHUS THOMPSON.
